Primary Examiner — Kelley Donnelly(74) *Attorney, Agent, or Firm* — Reed Smith LLP; Robert R. Riddle(57) **CLAIM**

The ornamental design for a support rack, as shown and described.

DESCRIPTION

FIG. 1 is a perspective view of a support rack in accordance with my new design;

FIG. 2 is a front elevation view thereof;

FIG. 3 is a top plan view thereof;

FIG. 4 is a rear elevation thereof;

FIG. 5 is a bottom plan view thereof;

FIG. 6 is a right side elevation view thereof; and,

FIG. 7 is a left side elevation view thereof.

The broken lines in the figures illustrate environmental structure only and form no part of the claimed design.
